United States Patent Office.

ERASTUS B. BIGELOW, OF BOSTON, MASSACHUSETTS.

Letters Patent No. 86,805, dated February 9, 1869.

IMPROVEMENT IN POWER-LOOM.

The Schedule referred to in these Letters Patent and making part of the same.

To all whom it may concern:

Be it known that I, ERASTUS B. BIGELOW, of Boston, in the county of Suffolk, and State of Massachusetts, have invented certain new and useful Improvements in Power-Looms; and I do hereby declare that the following is a full and exact description thereof, reference being had to the accompanying drawings, and to the letters of reference marked thereon.

These improvements are particularly applicable to power-looms, though some of them are applicable, and I intend to apply them, to other machines.

A part of my invention relates to a mode of engaging and disengaging the driving-pulley with the driving-shaft, whereby the usual loose pulley may be dispensed with, and a loom or other machine may be easily put in motion and quickly stopped, without straining the driving-belt, or heavy shocks to the machinery.

Another part relates to a mode of imparting a reversed movement to the loom, to put it in any desired position.

Another part relates to a mode of shipping and unshipping the loom, whereby the driving-pulley is connected and disconnected with the driving-shaft, the brake for arresting the movement of the loom is applied and released, and the mechanism for reversing the movement of the loom is brought into action.

Another part relates to a mode of unshipping the loom, and of arresting its movement when the shuttle fails to enter the shuttle-box.

Another part relates to a mode of stopping the loom when the filling is unsupplied.

Another part relates to a mode of operating the leaves of heddles, or harnesses.

Another part relates to a mode of governing the order of succession in which the shuttles are to be thrown.

Another part relates to a mode of governing the action of the mechanism which changes the shuttle-boxes; and

Another part relates to a mode of letting off the warps, and of regulating their tension.

The drawings clearly represent my improvements, and such parts of a power-loom as are necessary to illustrate them.

Figure 1 is a front elevation;

Figure 2, a rear elevation;

Figure 3, a right-hand end elevation;

Figure 4, a left-hand end elevation;

Figure 5 is a horizontal section, taken below the line A B on fig. 4;

Figure 6, a transverse section, looking toward the right-hand end of the loom;

Figure 7 is a similar section, looking toward the left-hand end of the loom; and

Figures 8, 9, 10, 11, 12, 13, 14, 15, 16, 17, 18, 19, 20, 21, and 22, are views of detached parts, which will be specially referred to in other parts of the specification.

A A represent the frame-work of the loom;

B, the breast-beam; and

e, the race-beam of the lay, which receives motion from the lay-shaft, d, in the usual manner.

The first part of my invention, or that which relates to the mode of engaging and disengaging the driving-pulley with the driving or lay-shaft, is as follows:

A wheel, which may be a brake-wheel, is affixed to the driving-shaft, on which the driving-pulley turns loosely, when the loom is at rest.

To engage and disengage the driving-pulley with the driving-shaft, to move or to stop the loom, two friction-levers are employed, which are curved to conform to the surface of the rim of the driving-pulley, and vibrate on studs projecting from the arms of the brake-wheel, on opposite sides of the driving-shaft.

A toggle-joint is formed between these two friction-levers, by two lever-arm, the inner ends of which ply in a mortise in the driving-shaft.

From this mortise to the end of the driving-shaft, a hole is formed, in which a rod slides, which rod is connected, at its inner end, with the lever-arms, and at its outer end with an elbow-lever, which is actuated by the loom-shipper.

The details of this apparatus are shown in figs. 8, 9, 10, 11, 12, 13, and 14.

The driving-pulley e, which has a thick rim, to act as a balance-wheel, turns loosely on the driving or lay-shaft d, and the brake-wheel f is fast on the lay-shaft d.

g are two friction-levers, which vibrate on the studs h, on opposite arms of the wheel f.

i are springs, affixed to the wheel f, which act on the levers g, and constantly tend to draw them away from the inner surface of the driving-pulley e.

j are lever-arms, the outer ends of which are inserted in cavities, suitably formed in the sides of the friction-levers g, whilst their inner ends abut together, and, when moved, act on the principle of a toggle-joint.

The abutting ends may either be made to correspond to arcs of circles, struck from the opposite ends of the levers, or they may be otherwise curved to increase or diminish the extent of motion imparted to the levers g, when moved through equal arcs.

They ply in a mortise, k, in the lay-shaft d, and are actuated by the sliding rod l, which slides endwise in a hole, which is also formed in the lay-shaft d.

The lever-arms j are connected with the sliding rod l, by the projections m, which ply in the recess n, in the side of the sliding rod l, (though I sometimes form this connection by inserting the abutting ends of the lever-arms j in a mortise formed in the sliding rod l, as represented in fig. 12,) so that when the sliding rod l is pressed inward toward the brake-wheel by the shipper, as will be hereafter explained, it sets the lever-arms like a toggle-joint, presses the friction-levers against the rim of the driving-pulley, and starts the loom, and when it is withdrawn, it loosens the lever-arms, or toggle-joint, disengages the friction-levers, and stops the loom.

When the toggle-joint is set, both friction-levers will simultaneously, and with equal pressure, be pressed

against the inner surface of the driving-pulley. The force with which they are pressed against the driving-pulley may be regulated by adjusting the length of one of the arms, which, for this purpose, is provided with an adjusting-screw and nut, *o*.

The outer surfaces of the friction-levers, which are pressed against the inner circumference of the driving-pulley, I prefer to cover with leather, or copper, to obtain a good friction-surface, though they may be otherwise prepared.

In driving looms for light work, I sometimes dispense with the friction-levers *g*, and cause the outer ends of the lever-arms *j* to press directly against the rim of the driving-pulley, in which case the outer ends of the lever-arms *j* are kept in position by guide-stands, extending from the arms of the brake-wheel; and instead of causing the lever-arms *j* to vibrate lengthwise of the shaft, I sometimes fit them to the mortise *k*, so as to fill it, and make the inner end of the sliding rod *l*, wedge-formed, which, when pressed between the inner ends of the lever-arms *j*, will cause them to press the friction-surfaces against the rim of the driving-pulley.

When wrought-iron lay-shafts are used, I sometimes make the part on which the driving-pulley turns, and in which the recesses or openings for the toggle-joint and sliding rod are formed, separately from the other part of the shaft, and of cast-iron, by which means it may be easily shaped.

The cast part of the shaft may be cast with the brake-wheel, or it may be cast with a flange or disk, and bolted to the hub of the brake-wheel, as represented in horizontal section in fig. 8.

Another object of this part of my invention is to facilitate the lubrication of the driving-pulley, and for this purpose I form a groove in the side of the part of the driving-shaft on which the driving-pulley turns, and fill it with woollen cloth, or other elastic material, capable of containing a reserved supply of oil, or other lubricating-material, and of gradually delivering it to the bearing-surface of the driving-pulley by contact therewith; and connect the groove with an opening in the outer end of the shaft, in such manner that the supply of oil may be replenished while the driving-pulley is in motion.

This arrangement is shown in fig. 10, in which *p* represents the part of the lay-shaft on which the driving-pulley turns; *q*, the groove, with the cloth, or other material, for containing a reserved supply of oil; and *r*, a hole in the collar *s*, through which the oil is introduced to the groove *q*, the collar *s* serving also to keep the driving-pulley in position.

Another part of my invention, or the mode of reversing the movement of the loom, may be understood as follows:

In the reversing-motions heretofore applied to looms, the gear which receives motion from the pinion or gear on the driving-pulley, is supported by fixed stands, and revolves continually, whenever the pulley which drives it revolves.

This part of my invention consists in giving to the reversing-mechanism a condition independent of the moving parts of the loom, so that it shall be in motion only when the loom is being moved backward, and be at rest at all other times.

For this purpose a gear or friction-roller is affixed to the hub of the driving-pulley, or to the hub of the loom-pulley, in case a fast and loose pulley are used, and another gear, though of larger diameter, is affixed to the driving or lay-shaft, or to the brake-wheel, as may be most convenient.

A vibrating bar, or carriage, capable of moving toward and from the driving-shaft, carries a gear or friction-roller, suitably formed to engage with the before-mentioned gear or friction-roller, on the driving-pulley, which gear or friction-roller acts on another gear, on

ries another gear, suitably formed to engage with the before-mentioned gear on the driving or lay-shaft, the whole of the intermediate gears being carried and supported by the before-mentioned vibrating bar or carriage, in such relation to the before-mentioned gears on the driving-pulley and driving-shaft, that whenever the vibrating bar or carriage is moved toward the driving-shaft, the gears on the driving-pulley and driving-shaft engage with their respective intermediate gears, and impart a backward movement to the loom, so long as they are thus held in contact, and when the vibrating bar or carriage is moved away from the driving or lay-shaft, far enough to draw the gears out of contact, the reversing-mechanism ceases to act, and remains at rest until the motion of the loom is to be again reversed.

Different views of a reversing-apparatus, thus arranged, are given in figs. 1, 2, 3, and 5.

t is the gear, or friction-roller, on the hub of the driving-pulley *e*, which, when the reversing-action takes place, acts on the gear or friction-roller *u*, which revolves on the stud *v*, and carries the gear *w*, which engages with and turns the gear *x*, on the outer end of the axis *y*, which axis, on its inner end, carries the gear *z*, which engages with and turns the gear *a'*, on the brake-wheel *f*, before described.

The axis *y* is supported by two arms, *b'*, which extend upward from a tube, *c'*, which oscillates on a stud, *d'*, and the stud *v* is supported by a bar, *e'*, the forward end of which is jointed to one of the arms, *b'*, whilst its rear end, being fork-shaped, embraces and is supported by the hub of the driving-pulley *e*.

From this description it will be obvious that when the tube *c'* is turned on the stud *d'*, so as to move the bar *e'* toward the driving or lay-shaft *d*, the reversing-gears will be brought into action; and when it is turned in the opposite direction, they will be separated, and the reversing-action cease.

The arm *f'*, which extends forward from the tube *c'*, is actuated by the weaver to throw the reversing-mechanism into and out of action, in a manner to be hereafter explained.

Another feature of this part of my invention is represented in fig. 9, and consists in employing the driving-belt to turn the reversing-mechanism, instead of a gear or friction-roller affixed to the hub of the driving-pulley, as above described.

In this modified arrangement, the driven friction-roller *u* is affixed to the axis *y*, and to effect the reversing-action, is pressed against the driving-belt, which, being between the friction-roller *u* and the driving-pulley, imparts motion to the friction-pulley *u*.

The intermediate gear *w*, for changing the direction of motion, is placed between the gear *z* and the gear *a'*, on the brake-wheel.

Another part of my invention, or that which relates to the mode of shipping and unshipping the loom, is as follows:

Two shafts, or axes, are applied near the breast-beam, which may extend across the loom, from side to side, and have shipping-handles on each end, the first, or shipping-shaft, being employed to start the loom, and to operate the brake for arresting its movement, and the second, or releasing-shaft, being employed to throw the loom out of gear, and to release the brake from the brake-wheel, to allow the loom to be turned without moving the shipper, and also, if a reversing-motion be employed, to bring the reversing-motion into action. This apparatus, and its connection with the loom, are represented in figs. 1, 3, and 5; but it will be more readily understood by the diagram, fig. 15.

g' is the shipping-shaft, and *h'*, the shipping-handles, by which the weaver turns the shipping-shaft to start the loom, and *i'* and *j'* are stops projecting from the loom-frame, which limit their movement.

which the driving-pulley is placed, has a latch-projection, k^1 , and a horizontal arm, l^1 , for purposes which will be presently explained, and also a depending arm, m^1 , which is connected with the apparatus before described, for connecting and disconnecting the driving-pulley with the driving-shaft.

n^1 is an elbow-lever, which vibrates on the stud o^1 , supported by the stand p^1 , the outer arm of which is fork-shaped, one prong being so formed as to act on the end of the sliding rod l , to press it inward to start the loom, as above explained, whilst the other, flying in the groove q^1 , withdraws the rod l , and stops the loom.

The inner arm of the elbow-lever n^1 is connected with the depending arm m^1 , by the connecting-rod, r^1 , so that when the shipping-handle h^1 is pushed forward against the stops j^1 , it starts the loom, and when it is drawn back against the opposite stop, i^1 , it stops the loom.

On one part of the shipping-shaft g^1 , a coiled spring, s^1 , is placed, one end of which is attached to the loom-frame, and the other to an adjusting-collar affixed to the shaft, so that the spring constantly tends to turn the shaft in the direction to stop the loom, and will do so whenever the shipping-handle h^1 is set free.

t^1 is a bent latch-lever, carried by the stud u^1 , the upper arm of which latches on to the latch-projection k^1 , before alluded to, whenever the shipping-handle h^1 is moved forward to start the loom, and holds it in position so long as it is desired to keep the loom in motion. Then, when it is desired to stop the loom, the latch-lever t^1 is tripped, and the spring s^1 throws it out of gear, as just explained.

v^1 is a brake-lever, which vibrates on a stud, w^1 , and is bent to conform to the surface of the brake-wheel f , on which it acts to arrest the movement of the loom when it is thrown out of gear.

x^1 is a latch-jointed connecting-rod, which connects the brake-lever v^1 with the arm l^1 , before mentioned.

When the shipping-handle h^1 is drawn back against the stop i^1 , to stop the loom, the arm l^1 assumes a horizontal position, and causes the stud y^1 , which connects it with the connecting-rod x^1 , to draw the brake v^1 firmly against the brake-wheel f . Then, when the shipping-handle h^1 is pushed forward against the stop j^1 , to start the loom, the stud y^1 is moved through an arc sufficient to set the brake free from the brake-wheel.

As it is necessary, sometimes, to release the brake, to turn the loom without moving the shipper, the connecting-rod x^1 is made in two parts, and formed with latch-projections, z^1 , by which they may be disconnected by the releasing-shaft, to release the brake when required.

The releasing-shaft a^2 has three successive actions: first, it trips the latch-lever, to throw the loom out of gear; secondly, it releases the brake from the brake-wheel; and, thirdly, it brings into action the reversing-motion; and these operations are effected in the following manner:

The shaft has affixed to it, at each end, a lever-arm, b^2 , which extends forward, to enable the weaver to work it conveniently, and the one on the driving-side of the loom is provided with a cam-projection, c^2 , on its side next to the loom, which acts on a corresponding cam-surface, d^2 , on the lower arm of the latch-lever t^1 , these cam-surfaces being indicated by dotted lines in figs. 3 and 15.

The shaft also carries another arm, e^2 , to the end of which a vertical rod, f^2 , is jointed, in which there are two slots, g^2 h^2 . In the slot g^2 is received a pin carried by the forward part of the connecting-rod x^1 , and in the slot h^2 is received a pin carried by the arm f^1 of the reversing-mechanism, which has been already described.

When it is desired to stop the loom, the weaver, by one or the other of the lever-arms b^2 , turns the shaft

a^2 , and causes the cam-projection c^2 to trip the latch-lever t^1 , and throw the loom out of gear. Then, if it is desired to turn the loom, for any purpose, the weaver turns the shaft a^2 further, and causes the lower end of the slot g^2 , acting on its pin, to disconnect the latch-projections z^1 , and release the brakes, which are drawn away from the brake-wheel by the counterbalance-weight j^2 , and sets the loom free to be turned in either direction. Then, again, if it is desired to reverse the movement of the loom, the weaver turns the shaft a^2 still further, and causes the lower end of the slot h^2 , acting on its pin, to raise the arm f^1 , and put the reversing-mechanism in action.

After the shaft a^2 has been turned by the weaver, as just explained, it is brought back to its original position by the coiled spring i^2 .

The two parts of the connecting-rod x^1 are guided, in their proper relation to each other, by the stand k^2 , whilst the check-nut l^2 prevents the counterbalance-weight j^2 from drawing the latch-projections z^1 out of latching-position when the shipping-handle h^1 is moved forward to start the loom.

I sometimes dispense with the releasing-shaft a^2 , and place the releasing-lever arm, or handle, b^2 , on the shipping-axis, or shaft, g^1 , and employ the releasing-lever arm, or handle, b^2 , to turn the shipping-shaft to throw the loom into gear, instead of employing separate handles on the shipping shaft for that purpose.

When the releasing-lever arm or handle is employed to throw the loom into gear, it is made to turn loosely on the shipping-shaft, in the direction in which it is moved to throw the loom out of gear, release the brake, and bring the reversing-motion into action, and to engage with the shipping-shaft by a latch-connection, when it is moved in the opposite direction, and so turn the shipping-shaft to throw the loom into gear.

Another part of my invention, or that which relates to the mode of unshipping the loom and arresting its movement when the shuttle fails to enter the shuttle-box, may be understood as follows:

A protecting-rod, u^2 , with the arms v^2 for acting on the shuttle-binders, (the shuttle-boxes, being well known, are not represented,) is applied to the lay of the loom in the usual way.

An arm, w^2 , (see figs. 3, 5, and 6,) is affixed to the protecting-rod u^2 , and extends backward from the lay, and has a hooked projection, x^2 , near its end, on its side next to the loom-frame, as indicated by dotted lines in figs. 3 and 6, which hooked projection is formed to engage with the hook y^2 , in the stand z^2 .

The stand z^2 is affixed to the upright lever a^3 , which vibrates on the stud b^3 , and carries a spring, c^3 , which serves to soften the shock consequent upon suddenly arresting the movement of the loom.

d^3 are stops which project from the frame, and serve to limit the movement of the lever a^3 .

The stand z^2 is bent round towards the frame, as shown in fig. 5, to support the rear end of the rod e^3 , the forward end of the rod e^3 being connected to the lower arm of the before-mentioned latch-lever t^1 , by a slot and pin, f^3 , as shown in fig. 16. The object of the slot is to allow the latch-lever t^1 to be tripped by the releasing-shaft without moving the rod e^3 .

The rod e^3 has a collar, r^3 , against which the stand z^2 strikes, when it throws the loom out of gear, and a spring, g^3 , which rests against the collar s^3 , and draws the rod e^3 into position after it has been thrown forward to stop the loom by the filling-stop motion, as will be hereafter explained.

The operation of this mechanism is as follows:

When the shuttle properly enters its box, and causes the shuttle-binder to push back one or the other of the arms v^2 , and thus turn the protecting-rod u^2 , the end of the arm u^2 will be depressed so as to bring its hook, x^2 , below the hook y^2 , when the lay advances to beat up the cloth, and the loom remains in gear; but

when the shuttle fails to enter the shuttle-box, and turn the protecting-rod, as just explained, the hook x^2 will engage with the hook y^2 , and the lay, by its advancing movement, will draw the lever a^2 forward, against the forward stop d^2 , which forward movement of the lever a^2 , causes the rod e^2 to trip the latch-lever t^2 , and throw the loom out of gear, whilst the spring c^2 relieves the force of the shock consequent upon the sudden arresting of the loom by the stop d^2 .

In place of the metallic spring c^2 , I sometimes use vulcanized India rubber.

The next part of my invention, or the mode of stopping the loom when the filling is unsupplied, will now be described.

The fingers which feel the thread, are formed on the forward ends of levers f^3 , which are carried by the lay, and jointed, at their rear ends, to the stands q^3 , there being one set of such fingers at each end of the lay. These two sets of fingers are connected together, so as to move in unison, by means of the shaft j^3 , which extends from one to the other, below the race-beam, and is supported by the stands q^3 , the arms f^3 , which extend from the shaft, being connected to their respective finger-levers, f^3 , by the rods h^3 .

To raise the fingers f^3 for the passage of the shuttle, an arm, l^3 , extends from the shaft j^3 , which is actuated by a fixed cam-surface, m^3 , projecting from the loom-frame.

Another arm, n^3 , is affixed to the shaft j^3 , and carries a counterbalance-weight at its rear end, while its forward end is suitably formed to engage with the hook-like projection o^3 on the rod e^3 before described. This arrangement is clearly shown in fig. 16.

As the lay moves forward, after a shuttle has been thrown, the stand m^3 allows the fingers f^3 to fall by their own gravity, and, if the filling is not supplied, the fingers pass through grids p^3 , formed in the upper surface of the race-beam, as shown in fig. 5, and cause the forward end of the arm n^3 to rise to a position to engage with the hook-projection o^3 , so that the lay, as it advances, will move the rod e^3 forward, trip the latch-lever t^3 , and throw the loom out of gear; but, if the filling is duly supplied at either end of the lay, it will support the fingers, and prevent them from passing through the grids, thereby causing the arm n^3 to pass clear of the projection o^3 , and allow the loom to continue in motion.

The next part of my invention, or that which relates to the mode of operating the leaves of heddles, or harnesses, may be understood as follows:

The leaves of heddles q^3 are hung in the loom in the usual way, and the vertical heddle-levers r^3 , which operate them, are placed side by side, in a vertical position, at a side of the loom, and vibrate toward and from the loom on a central axis, s^3 .

The upper bars of the leaves of heddles q^3 are connected with the upper arms of the vertical heddle-levers r^3 by cords or chains t^3 , guided by guide-pulleys w^3 , whilst their lower bars are connected by cords or chains v^3 , passing around guide-pulleys w^3 , to the lower arms of the levers r^3 , so that, when any one of the vertical heddle-levers r^3 is moved in one direction, it will raise the leaf of heddles with which it is connected, and, when moved in the opposite direction, it will depress it.

To operate the vertical heddle-levers r^3 , two horizontal vibrating bars, x^3 and y^3 , are placed parallel to their axes, near their lower ends, one on either side of the series, which vibrate on axes z^3 , perpendicular to the cloth-forming line, and open and close, like the blades of shears, at each beat of the lay. When they are closed, they press against the edges of the vertical heddle-levers r^3 , and bring them all to a vertical position, and close the shed of the warps; and, when opened, they, by means soon to be explained, engage with and draw some of them in one direction, and some in another, and form an open shed.

By placing the axes z^3 of the vibrating bars x^3 and y^3 perpendicular to the cloth-forming line, the bars x^3 and y^3 , when opened, will form an angle corresponding to the angle of the open shed of the warps; and, by thus moving the several leaves of heddles varying distances, according to their distance from the cloth-forming line, will make an even shed.

To cause the horizontal vibrating bars x^3 and y^3 to engage with the vertical heddle-levers r^3 , to form an open shed, horizontal latch-levers a^3 are jointed to the lower ends, that is, below the axes of the vertical heddle-levers r^3 , just above the horizontal vibrating bars, which latch-levers are provided at both ends with depending latches or hooks b^3 , so placed, with respect to the horizontal vibrating bars, as to latch or hook on to one or the other of them when they are closed, to bring the vertical heddle-levers r^3 into a vertical position, as above explained, the axes of the latch-levers being so placed that only one of their latches or hooks can engage with the horizontal vibrating bars at the same time; that is to say, when one end of the latch-levers is depressed, so as to bring its latch, or hook, into contact with its horizontal vibrating bar, the latch, or hook, on its opposite end will clear the other horizontal bar, and *vice versa*, and, whether the latches, or hooks, which raise the heddles, or those which depress them, are brought into action, depends on the direction in which the latch-levers are tilted.

It will thus be obvious that the leaves of heddles may be caused to rise or fall, in conformity with any desired pattern, by merely raising or depressing the ends of the latch-levers; and the manner in which this is effected I will now describe.

A series of balance-levers, c^3 , corresponding in number with the vertical heddle-levers r^3 , is placed in a horizontal position on an axis, d^3 , near the axis s^3 of the levers r^3 , and parallel to it.

The inner ends of the balance-levers c^3 are severally connected with the outer ends of the latch-levers a^3 by connecting-rods e^3 , the lower ends of which are jointed to their respective latch-levers a^3 , whilst their upper ends ply in grooves formed in projections f^3 on the sides of the vertical heddle-levers r^3 , and terminate in a hook, so formed as to hook on to the ends of the balance-levers c^3 , as shown in fig. 17.

Springs f^3 act on the balance-levers c^3 , and tend constantly to depress their outer ends, so that, when they are left unsupported by the pins of the pattern-surface, they will be depressed, and, through the action of the connecting-rods e^3 , raise the outer ends of the latch-levers a^3 , and cause the latches b^3 , on their inner ends, to engage with the horizontal vibrating bar x^3 , and raise the leaves of heddles with which they are connected; but if the outer ends of the balance-levers are raised, the weight of the rods e^3 will depress the outer ends of the latch-levers, and cause their latches b^3 to engage with the horizontal vibrating bar y^3 , and depress the leaves of heddles. Instead of the springs f^3 , for depressing the balance-levers c^3 , a weight, formed on their outer ends, as represented in fig. 17, may be substituted.

To determine which of the balance-levers c^3 shall be raised, and which shall be depressed, to cause their respective leaves of heddles to rise or fall in conformity with any desired pattern of cloth, a pattern-surface, carrying cam-like projections, is employed, which has imparted to it a continuous rotary movement, and is so placed, with respect to the outer ends of the balance-levers c^3 , that, when any of the cam-like projections pass under them, they will be raised, whilst those over the parts of the pattern-surface which have no cam-like projections will remain at rest, and thus cause their leaves of heddles to rise or fall accordingly. This pattern-surface may be in the form of a cylinder, as represented in the drawings, or it may consist of a pattern-chain, composed of chain-links, pins, and rollers,

carried by a rotating axis, or cylinder, suitably formed to support it.

The pattern-cylinder is marked g^4 , and is carried by an axis, h^4 , which turns in a long bearing, i^4 , on the stand j^4 , which is so arranged as to leave one end of the cylinder free for the easy removal and replacing of a pattern-chain.

k^4 are the cam-like projections on the pattern-cylinder g^4 , which act on similar projections, l^4 , on the under side of the balance-levers c^4 , the projections l^4 being so shaped that the projections k^4 will act upon them when the cylinder g^4 is turned in either direction.

By connecting the latch-levers with the balance-levers by a loose connection, as above described, I am enabled to give to the pattern-surface a continuous rotary motion, for, by means of this loose connection, the pattern-surface may act on the balance-levers, to govern their action during the time the catch-levers are engaged with the vibrating-bars which actuate them. I am also enabled to reverse the motion of the loom, to put it in any desired position, without changing its relation to the harness-motion, for, when the loom is turned backward, the pattern-surface turns backward in unison with it.

Another important feature of this part of my invention, is the reduction of the width of the pattern-surface. Heretofore, the pattern-surface has been as wide, or nearly as wide as the space occupied by the leaves of heddles and the levers which operate them, whereas, by my improved arrangement, it need not be more than one-fourth part as wide.

Fig. 5 exhibits a plan of the balance-levers, c^4 , and pattern-surface, which acts on them, the balance-levers being formed as therein indicated; that is to say, their inner ends occupy a space equal, or nearly equal to the space occupied by the leaves of heddles, so that the connecting-rods which connect them with the latch-levers may be in a line with the vertical heddle-levers, whilst their outer arms are contracted to the space corresponding to the reduced width of the pattern-surface, the inner arms of the series of balance-levers on each side of the central balance-lever being bent toward the central one.

From this description, it will be seen that the pattern-surface may be reduced to any practicable limit, by contracting the arms of the balance-levers, on which it acts, in a corresponding degree.

A continuous rotary motion is communicated to the pattern-surface cylinder g^4 by the upright shaft m^4 , which receives motion from the lay-shaft d , through the mitre-gears n^4 .

The upright shaft m^4 is supported by the bearing-stands o^4 and p^4 , and, through the mitre-gears q^4 , imparts motion to the horizontal shaft r^4 , which carries a worm, s^4 , which takes into the gear t^4 , on the axis h^4 , and turns the cylinder g^4 .

The inner end of the horizontal shaft r^4 is supported by the bearing-stand o^4 , and its outer end, by another stand, u^4 , the last-mentioned stand being provided with a slot, to allow the shaft to be raised to disengage the worm s^4 from the gear t^4 , to adjust the pattern-cylinder g^4 when required.

The shaft r^4 is held in position by an elbow-lever, v^4 , which may vibrate on a stud, w^4 , and, when it is in the position shown in the drawings, the lower end of its vertical arm holds the shaft in gear, but, by turning it aside, (which the weaver can easily do by raising its horizontal arm,) the shaft is free to be raised out of gear.

The upright shaft m^4 also imparts the required vibratory motion to the horizontal vibrating bars x^3 and y^3 , before mentioned. It carries on its lower end a double crank, whose crank-pins are on opposite sides of the shaft, one of the crank-pins, x^4 , plying in a curved slot in the end of the horizontal bar, x^3 , and the other pin, y^4 , in a similar slot in the end of the horizontal bar, y^3 ,

so that, at each revolution of the shaft, the horizontal bars, x^3 and y^3 , are caused to open and close, as above described. These parts are clearly shown in fig. 22.

The slots may be curved, more or less, according to the time it is desired to have the shed of the warps remain open for the passage of the shuttle.

The horizontal bars, x^3 and y^3 , are faced with vulcanized India rubber, z^4 , fitted into recesses formed in their sides, where they come against the vertical heddle-levers, r^3 , so as to ease the blow of the horizontal bars against the levers; and the India rubber also serves as a spring to prevent the latches b^4 escaping from the horizontal bars, except at the time when the India rubber is compressed by the horizontal bars closing upon the vertical heddle-levers r^3 , in their central position, at which time the latch-levers a^4 are shifted.

The next part of my invention, or that which relates to the mode of governing the order in which the shuttles are thrown, is as follows:

Two picker-levers are employed, as is usual, one on either side of the loom, which are marked a^5 , and vibrate on the studs b^5 . Their forward ends may be connected with the picker-staves in the usual way, but, as these connections form no part of my invention, they are not represented. Their rear ends carry rollers c^5 , which, when the shuttles are thrown, are acted on by their respective cams d^5 , on the lay-shaft d .

Now, as the cams d^5 are capable of acting on their rollers c^5 , at each revolution of the lay-shaft d , it will be seen that if the rollers c^5 remain continually in the path of the cams d^5 , the picker-staves at each side of the loom will be actuated simultaneously.

To avoid this, and to enable the picker-levers to be moved in and out of position to be acted upon by their cams, they are made capable of sliding endwise on the studs b^5 , and are guided and supported by the upright oscillating levers e^5 , which are so connected together by the rod f^5 that they move in unison, so that when the rod f^5 is moved in one direction, it will push one of the levers a^5 into position to be acted upon by its cam, and the other lever, a^5 , out of position to be so acted upon, and *vice versa*, the length of the rod f^5 being so adjusted that only one of the levers a^5 can be acted upon at the same time.

The mode of pushing the rod f^5 to and fro, to cause the shuttles to be thrown from either side of the loom in the required order, I will now explain.

A lever, which is marked g^5 , is placed upon the axis s^5 , by the side of the vertical heddle-levers r^3 , before described, and is connected with the rod f^5 by another rod, h^5 .

The lever g^5 also carries, at its lower end, a latch-lever, i^5 , which is jointed thereto, and connected with a balance-lever, j^5 , by the rod k^5 , through a loose connection, in the same manner as the latch-levers a^4 are connected with the balance-levers c^4 .

The latch-lever i^5 has no depending latches or hooks, such as the latch-levers a^4 have, but the ends thereof engage with the projections l^4 , on the horizontal vibrating bars x^3 and y^3 , when brought into the required position to do so.

This form of the latch-lever i^5 is required, for the reason that the horizontal vibrating bars x^3 and y^3 act upon it when they are being closed, whereas they act on the latch-levers a^4 , when they are being opened, a variation made necessary by the fact that the picker-levers have to be moved at a different stage of the operation of the loom from that in which the shed is formed.

When the inner end of the latch-lever i^5 is depressed, so as to bring it in contact with the projection l^4 on the horizontal vibrating bar x^3 , the bar x^3 , where it closes, will push the picker-levers a^4 in the direction of the left-hand end of the loom, and cause the left-hand picker-lever to be acted upon by its cam. Then, when the outer end of the latch-lever i^5 is depressed, so as

to bring it in contact with the projection F on the horizontal vibrating bar y^3 , the bar y^3 , when it closes, will push the picker-levers a^3 in the direction of the right-hand end of the loom, and cause the right-hand picker-lever to be acted upon by its cam, so that to determine the side of the loom from which the shuttle shall be thrown, it is only necessary to raise or depress the ends of the latch-lever i^3 accordingly.

After the lever g^3 is moved in one direction, the inertia and friction of the parts connected with it will retain it in position until it is moved in the opposite direction, the lower end of the lever g^3 being so arranged as to clear the horizontal vibrating bars x^3 and y^3 .

The order in which the shuttles are to be thrown is governed by a pattern-surface carried by the cylinder g^4 , which acts on the balance-lever j^3 in the same manner as the pattern-surface before described acts on the balance-levers c^4 , though the pattern-surface, which governs the order in which the shuttles are thrown, is placed on the pattern-cylinder in a position to act on the balance-lever j^3 at an earlier stage of the operation of the loom than the pattern-surface, which governs the action of the leaves of heddles, acts on the balance-levers c^4 ; on account of the difference in the relative time in which the shuttles and leaves of heddles are to be actuated.

By placing the pattern-surface, which governs the order in which the shuttles are thrown, on the same axis or cylinder which carries the pattern-surface which governs the action of the leaves of heddles, I am enabled to operate them both by one movement, and thus to simplify the mechanism of the loom, and also to adjust them together by one action, whenever they require to be adjusted to restore the "pick" after it has been lost by the failure of the filling, or by the "picking out" of bad cloth.

The next part of my invention, or that which relates to the mode of governing the action of the mechanism which shifts the shuttle-boxes, I will now describe.

m^3 represents an oscillating shaft, which extends across the loom, and carries, at each of its ends, an arm, n^3 .

The arms n^3 extend forward, and are bent, as shown by dotted lines in fig. 5, so as to bring their ends into a suitable position to be attached to the shuttle-boxes, which may be done by rods or chains in the usual way.

The shuttle-boxes, and the means by which they are connected with the arms just described, are not represented, as they form no part of my present invention.

The shaft m^3 carries another arm, o^3 , which is bent to clear the stand p^3 , and carries a roller, p^3 , which rests on a cam, q^3 .

The cam q^3 turns on a stud, r^3 , and has affixed to it two ratchet-wheels, u^3 , with their teeth facing in opposite directions, and a brake-wheel, s^3 , on which the brake-lever t^3 acts, to hold it in position.

The cam q^3 is formed with rising and falling surfaces, with concentric parts, at varying distances from its centre, equal to the motion required to be given to the arm o^3 to shift the shuttle-boxes.

At each change of the shuttle-boxes, the cam q^3 is turned in one or the other direction equal to the space of a tooth of the ratchet-wheels u^3 , and remains at rest during the time the shuttle-box thus brought into action is to be employed, and until another change of boxes is required.

The cam q^3 raises the shuttle-boxes and allows them to fall by their own gravity, the shuttle-boxes rising or falling, according to the shape of the cam, and the direction in which it is turned.

The mode of governing the action of the cam q^3 , or any other mechanism which may be employed to shift the shuttle-boxes, to determine the order in which the shuttle-boxes are to be brought into use, is as follows:

A horizontal lever, which is marked v^3 , vibrates at

its forward end on a stud, w^3 , while to its rear end two depending bars x^3 are jointed, the lower ends of the depending bars x^3 being provided with hooks suitably formed to engage with the teeth of the ratchet-wheels u^3 , before described.

The horizontal lever v^3 has an arm, y^3 , extending downward from it, which rests on a cam, z^3 , on the lay-shaft d , which cam is so shaped as to raise the lever during the part of the revolution of the lay-shaft in which it is required to change the shuttle-boxes, and to descend during the other part.

As the lever v^3 vibrates, it carries the depending bars x^3 up and down with it.

a^3 are lever-arms, which oscillate on the stud b^3 , and are provided with recesses, in which the depending bars x^3 ply, and by which they are guided, the weight of the depending bars x^3 causing them to rest against the bottom of the recesses.

c^3 are T-formed balance-levers, which oscillate on a stud, d^3 , their rear horizontal arms being provided with counterbalance-weights, which tend to depress them until they strike the stop-pin e^3 .

The depending arms of the T-formed balance-levers c^3 are connected to their respective lever-arms a^3 by connecting-rods f^3 , one being attached above the axis b^3 , and the other below it, in order that the counterbalance-weights just mentioned may tend to draw both of the bars x^3 away from their respective ratchet-wheels, u^3 ; and, so long as the rear arms of the T-formed balance-levers c^3 rest on the stop-pin e^3 , their counterbalance-weights hold the hooks of the bars x^3 out of contact with their ratchet-wheels, and they ascend without acting upon them; but, when either of the counterbalance-weights is raised, they turn the lever-arms a^3 , so as to allow the bar x^3 , with which it is connected, to move, by its gravity, towards its ratchet, u^3 , and to engage with it when it ascends, and turn it the space of one tooth, and change the shuttle-boxes.

The forward arms of the T-formed balance-levers c^3 are, respectively, connected with the inner arms of other horizontal balance-levers, g^3 , which vibrate on the stud d^3 , and have their outer arms formed with cam-like projections, like the balance-levers c^4 , before described.

From this description, it will be seen that, when either of the outer arms of the horizontal balance-levers g^3 is raised, it will cause the bar x^3 , with which it is connected, to engage with its ratchet-wheel, and change the shuttle-boxes; but, so long as they remain unraised, the bars x^3 will vibrate without producing such change, so that, to cause the shuttle-boxes to be changed in the order required, it is only necessary to raise the outer arms of the balance-levers g^3 accordingly.

This is effected by a pattern-surface, with cam-like projections, which acts on the projections on the balance-levers g^3 in the same manner as the pattern surface, which governs the action of the leaves of heddles, acts on the projections of the balance-levers c^3 .

The pattern-surface, which governs the shifting of the shuttle-boxes, is carried by the same axis-cylinder, g^4 , which also carries the pattern-surfaces which govern the order in which the shuttles are thrown, and in which the leaves of heddles rise and fall, so that the three pattern-surfaces move together in unison, whether the loom is turned forward or backward, and may all be adjusted by one action.

Though the three pattern-surfaces are all carried by one axis-cylinder, I prefer to make the pattern-chain which governs the action of the leaves of heddles separate from the chains which govern the order in which the shuttles are thrown, and in which the shuttle-boxes are changed; but the two last named may be conveniently joined together.

The next part of my invention to be described relates to the mode of letting off the warps, and of governing their tension.

h^6 is the warp-beam, from which the warps, when being woven, pass, over a vibrating roller, through the heddles, to the breast-beam of the loom, in the usual way.

The warp-beam h^6 , at one end, carries a gear, i^6 , which takes into a worm, j^6 , on a horizontal shaft, k^6 , which is supported by a stand, l^6 , affixed to the loom-frame, as represented in figs. 4 and 5.

The shaft k^6 also carries a ratchet-wheel, m^6 , which is affixed to the shaft k^6 , and a horizontal lever-arm, n^6 , which, at its inner end, turns loosely on the shaft, whilst its outer end terminates in the form of a segment.

The horizontal lever-arm n^6 carries a pawl, o^6 , which is jointed to it, and acts on and turns the ratchet-wheel m^6 , when it is vibrated.

A horizontal lever, p^6 , vibrates, at its forward end, on the stud w^6 , before mentioned, whilst its rear end is connected with the segment of the lever-arm n^6 by a strap, q^6 .

The lever p^6 has an arm, which extends downward, and rests on the cam r^6 , on the lay-shaft d , which cam vibrates the lever p^6 , and causes the pawl o^6 to turn the ratchet m^6 , and is so shaped as to allow it to descend, to renew its hold on the ratchet, whilst the shed is open, and the warps are at rest.

The degree of motion which the cam r^6 imparts to the lever p^6 should be sufficient to deliver out the required length of warps on an empty warp-beam; but it will be seen that, if the lever p^6 were allowed to descend, and turn the warp-beam a given distance at each vibration, it would deliver out the warps unequally; that is, the greater the diameter of the warps on the warp-beam, the greater would be their length given out.

To govern the extent of the vibrations of the lever p^6 , and thus cause it to deliver only the length of warps required to make the cloth being woven, a vibrating roller, s^6 , over which the warps pass, is made to vibrate to their tension.

The vibrating roller s^6 is carried, at each end, by levers t^6 , which vibrate on studs u^6 , extending from stands v^6 , which are affixed, in a manner to be adjustable, to the frame of the loom.

The rear arms of the levers t^6 receive and support the gudgeons of the vibrating roller s^6 , whilst their rear ends terminate in segments of gears, which engage with pinions w^6 , on a tension-shaft, x^6 .

The tension-shaft x^6 extends across the loom, from side to side, and is supported by bearings formed in the stands v^6 , which carry the studs u^6 , so that, when necessary, all the parts of the apparatus may be adjusted together.

When the warps are taken from the vibrating roller s^6 , the segment-gears will have a tendency to become disengaged from their pinions, to prevent which, slots y^6 are formed in the segment-arms of the levers t^6 , in which projections z^6 , extending from the stands v^6 , ply, and limit their motion.

Around the tension-shaft x^6 a spiral spring, a^6 , is coiled, one end of which is affixed to one of the projections z^6 , and the other, to an adjusting-collar, b^6 , which is affixed to the tension-shaft x^6 , the tendency of the spring a^6 being in the direction to raise the vibrating roller s^6 and tighten the warps, and as the spring a^6 is adjusted, so will be the tension of the warps.

The tension-shaft x^6 carries an elbow-lever, c^6 , the upright arm of which is formed, on one of its edges, with one or a series of steps, d^6 , the series gradually increasing in distance from a radial line toward its axis, and the horizontal lever p^6 , before mentioned, has a projection, e^6 , on its side, suitably formed to rest on the steps d^6 when they are brought under it.

The hub of the elbow-lever c^6 is so fitted to the shaft x^6 that it may turn freely upon it, but the elbow-lever c^6 is held in a position to oscillate in unison with the tension-shaft, by the weight of its horizontal arm, which

draws it against a stop-projection, f^6 , affixed to the tension-shaft x^6 . But if, from any cause, the shaft x^6 is turned so as to bring the steps d^6 forcibly against the projection e^6 , the tension-shaft x^6 will turn in the hub of the lever c^6 , and injury to the parts be prevented.

For convenience of construction, I sometimes change the position of the parts just described, so as to have the arm of the elbow-lever c^6 , which carries the steps d^6 , extend downward from the tension-shaft x^6 , instead of upward, as is represented in the drawings. Its regulating-effect, however, is the same in both cases.

It will be seen, from what has been stated, that the spring a^6 tends to keep the warps at a given tension, and that the lever p^6 , if allowed to vibrate at each beat of the lay, to the extent of the movement of its cam r^6 , will give out a greater length of warps than is required, but the delivery of the warps is governed and adapted to the requirements of the cloth being woven, as follows:

When more warps are given out than are taken up in the cloth, the length of the warps between the warp-beam and the cloth will be proportionately increased, and allow the spring a^6 to turn the tension-shaft x^6 , and raise the vibrating roller s^6 , and when fewer warps are given out than are required, their diminished length will depress the vibrating roller s^6 , and turn the tension-shaft x^6 in the opposite direction; and when the tension-shaft x^6 turns the elbow-lever c^6 , so as to bring some one of the steps d^6 under the projection e^6 , it will arrest the downward movement of the lever p^6 , and limit its action on the yarn-beam; then, when the turning of the tension shaft x^6 withdraws the steps d^6 away from the projection e^6 , the lever p^6 will descend a greater distance, and have a greater action on the yarn-beam, so that the length of warps given out at each beat of the lay will be governed by the position of the steps d^6 , as governed by the condition of the warps themselves.

Except when weaving the lighter fabrics, the action of the spring a^6 will not be sufficient to resist the blow of the lay in beating up the cloth, and to give increased rigidity at the time of the beat-up, an arm, g^6 , is affixed to the tension-shaft x^6 , and extends downward, and has a rod, h^6 , jointed to it, which extends forward, and is supported by the stand i^6 , affixed to the lay.

j^6 is a cylinder, of vulcanized India rubber, the position of which on the rod h^6 is adjusted, to give the required resistance, by the adjusting-nuts k^6 .

When the lay moves forward to beat up the cloth, the stand i^6 strikes against one end of the rubber cylinder or buffer j^6 , whilst its other end rests against the adjusting-nuts k^6 , thus causing the rod h^6 to hold the vibrating roller s^6 sufficiently firm to resist the beat-up, the spring-action of the rubber cylinder or buffer adapting the degree of resistance to the varying position of the vibrating roller s^6 , and to the varying texture of the cloth and size of the filling, such as occur in the weaving of fabrics like ingrain carpeting.

Another feature of this part of my invention relates to a mode of gradually diminishing the tension of the warps when the shed is opened, and of gradually increasing it when the shed is closed, and to a degree sufficient to resist the blow of the lay in beating up the cloth, the means by which these results are accomplished being represented in figs. 19 and 20.

The tension-shaft x^6 has coiled around it a spiral spring, l^6 , one end of which is attached to an adjusting-collar, m^6 , which is affixed to the tension-shaft, whilst the other end is attached to the hub of an arm, n^6 , which turns loosely on the tension-shaft.

The arm n^6 is connected with the lay by a connecting-rod, o^6 , so adjusted, with respect to its length, that when the lay moves forward to beat up the cloth, it will draw the end of the arm n^6 forward, and tighten, that is, increase the action of the spring l^6 , and thereby

increase the tension of the warps, and, when it is moved backward, it will slacken the tension of the spring and diminish the tension of the warps.

The action of the spring is so adjusted that, when it is slackened by the backward movement of the lay, it will give the required degree of tension to the warps when the shed is open; then, as the lay is moved forward, and the shed is closed, the increased action thus given to the spring will increase the tension of the warps, so as to resist the blow of the lay in beating up the cloth.

This mode of gradually diminishing the tension of the warps as the shed is opened, and of increasing it when the shed is closed and the cloth beat up, avoids all unnecessary strain upon them, and is highly advantageous in working such as are tender and easily broken.

Having thus fully described my invention, and pointed out some of the modifications of which it is susceptible, without departing from its distinguishing principles,

What I claim, and desire to secure by Letters Patent, is—

1. The rod vibrating endwise in a central hole in the driving-shaft, in combination with the actuating-lever arms, carried by the driving-shaft, and the friction-surfaces, which are pressed against the rim of the driving-pulley, and released therefrom, substantially as specified, for the purpose of engaging and disengaging the driving-pulley and driving-shaft.

2. Also, the combination of the mechanism, herein described, for stopping and starting power-looms, consisting of a driving-pulley, which turns loosely on the driving-shaft when the loom is at rest, friction-surfaces carried by the driving-shaft, a rod capable of vibrating endwise in a central hole in the driving-shaft, and the loom-shipper, by which the said rod is moved in one direction to press the friction-surfaces against the rim of the driving-pulley to start the loom, and in the opposite direction to stop the loom.

3. Also, in combination with a driving-pulley, which is engaged and disengaged with the driving-shaft by friction-surfaces, actuated by a sliding rod, as herein specified, the means herein described of lubricating the driving-pulley, consisting of a groove formed in the side of the driving-shaft, filled with cloth, or other elastic absorbent material, for containing and imparting a reserved supply of oil, or other lubricating-material, as described.

4. Also, in combination with a driving-pulley revolving continuously in one direction, and having mechanism by which it may be engaged with and disengaged from the driving-shaft, the mechanism herein described for producing the reverse motion of the driving-shaft, substantially as set forth.

5. Also, a vibrating lever, in combination with a loom-shipper, a brake for arresting the movement of the loom when thrown out of gear, and a reversing-mechanism, for reversing the movement of the loom, when said lever is employed, first, to throw the loom out of gear, second, to release the brake and set the loom free, and third, to bring a reversing-mechanism into action, substantially as described.

6. Also, the combination of mechanism, herein described, for arresting the movement of the loom when the shuttle fails to enter the shuttle-box, consisting of a lever, and a spring interposed between it and a fixed stop, a rod by which the lever releases the shipping-shaft, and a hook, on which a hook on the projecting rod acts, to bring the lever into action, substantially in the manner and for the purpose specified.

7. Also, the combination of mechanism, herein described, for stopping the loom when the filling is unsupplied, consisting of grids formed at each end of the race-beam in its upper surface, two sets of fingers, which feel the thread on the grids, a shaft by which

the two sets of fingers are connected together, a fixed cam by which the fingers are raised for the passage of the shuttle, and an arm, which acts on a rod to throw the loom out of gear, substantially as specified.

8. Also, the latch-levers, combining with the balance-levers by means of a loose connection, whereby the pattern-surface may act on the balance-levers during the time the latch-levers are engaged with the vibrating bars which actuate them, and whereby the pattern-surface may have a continuous rotary motion, substantially as described.

9. Also, the combination of mechanism, herein described, for operating the leaves of heddles, consisting of the vertical heddle-levers with which the leaves of heddles are connected, the horizontal vibrating bars which actuate them, the latch-levers, and the balance-levers, and the connecting-rods, or other equivalent loose connections, and the pattern-surface by which the several leaves of heddles are caused to rise or fall, in accordance with any desired pattern of cloth, substantially as described.

10. Also, in combination with the above, the horizontal vibrating bars, having their axes in a plane, vertical to the cloth-forming line, or nearly so, in combination with the vertical heddle-levers, so as to form an even shed, as above specified.

11. Also, in combination with vibrating bars, that operate a series of heddle-levers, the elastic cushions, that serve to ease their action on the levers on which they act, and retain the latch-levers in proper connection with the bars, as above described.

12. Also, the series of balance-levers, constructed as described, and acted on by the pattern-surface, within a narrow space, as compared with that occupied by the leaves of heddles, so that a comparatively narrow pattern-surface may be employed, as above described.

13. Also, the combination of mechanism, herein described, for governing the order of succession in which the shuttles are thrown, consisting of a lever placed at a side of the series of heddle-levers, and so connected with picker-levers as to cause them to vibrate in unison with it, a latch-lever, acted on by the closing-movement of the vibrating bars which actuate the heddle-levers, a balance-lever, which is connected with the latch-lever by a connecting-rod, or other equivalent loose connection, and a pattern-surface which acts on the balance-levers, substantially as and for the purpose described.

14. Also, the combination of mechanism, herein described, for governing the action of the mechanism which shifts the shuttle-boxes, consisting of a continuously-revolving pattern-surface, acting on balance-levers, and the parts which connect the balance-levers with the mechanism which shifts the shuttles, whereby the governing-action of the continuously-rotating pattern-surface is transmitted to the mechanism which shifts the shuttle-boxes, substantially as described.

15. Also, in combination, the mechanism for governing the rising and falling of the leaves of heddles, for governing the order of succession in which the shuttles are thrown, and the mechanism for shifting the shuttle-boxes, when the same are actuated by pins on one pattern-cylinder, substantially as described.

16. Also, the combination of mechanism, herein described, for giving tension to the warps, consisting of the vibrating roller over which the warps pass, the tension-shaft, and spring, or its equivalent, which gives tension to the warps, the levers, which carry the vibrating roller, and the pinions which connect them with the tension-shaft, when these parts are supported by stands above the yarn-beam, and caused to co-operate, in the manner and for the purpose specified.

17. Also, in combination with a tension-shaft, arranged and operated to give tension to the warps, as

herein described, a lever, provided with one or more steps, and operated to govern the delivery of the warps, substantially as described.

18. Also, in combination with a tension-shaft, arranged and operated to give tension to the warps, as herein described, the means, herein described, of giving firmness to the vibrating roller at the time of the beat-up, consisting of an arm affixed to the tension-shaft, and connected with the lay and a spring or rubber buffer, upon which the lay acts to hold the vibrating roller, in the manner and for the purpose described.

19. Also, in combination with a vibrating roller, over which the warps pass, a spring-arrangement, whereby the tension of the warps is gradually diminished whilst the open shed is being formed, and gradually increased, to an extent to resist the beat-up, whilst the shed is being closed, substantially as described.

E. B. BIGELOW.
